UNITED STATES PATENT OFFICE.

HAROLD L. WATKINS AND LA VERE J. EVELAND, OF LOS ANGELES, CALIFORNIA.

FABRIC PUFFER.

Application filed January 8, 1927. Serial No. 159,892.

This invention relates to a fabric puffer, and an object is to provide a renovating apparatus that is adapted to puff the nap of garments and the like into its natural position to cause the material to appear to be new in addition to being clean.

Another object of the invention is to provide a fabric puffer that is adapted to renovate garments without injuring their fabric. That is the apparatus is constructed so that only dry steam contacts with the material being renovated so that injurious moisture is not left therein to damage the fabric after it is cleaned.

Another object of the invention is to provide a fabric puffer on which fur trimmed garments can be renovated without injury to the fur. As is well known steam is injurious to fur trimming; consequently this apparatus is constructed so that a garment can be renovated without steam contacting with the fur trimming. Heretofore such trimmings have been removed from the garments before they are renovated; but by means of our apparatus the fur trimmings need not be removed while the garments are steam cleaned, thereby saving a large amount of time and cost.

Another object of the invention is to provide means for concentrating the steam on the seams, hems and folds of cloth, so that they can be renovated or cleaned independently of the body of the goods.

A feature of invention is shown in the arrangement of the pipes of the heating coil that are inclined downwardly from their inlet to their outlet ends so that water from condensation will flow out of the coil by gravity.

Other objects, advantages and features of invention may appear from the accompanying drawings, the subjoined detailed description and the appended claims.

The accompanying drawings illustrate the invention.

Figure 1 is a side view of a fabric puffer that is constructed in accordance with this invention; showing its steam shell in vertical section, some of the parts of which are semi-diagrammatically indicated.

Fig. 2 is an enlarged cross section on line 2-2 of Fig. 1.

Fig. 3 is an enlarged fragmental cross section on line 3-3 of Fig. 1; showing the

means for securing the steam pipes to a support so as to hold the steam shell in position to have sleeves of garments placed thereon.

Fig. 4 is a longitudinal section on staggered line 4-4 of Fig. 1, showing the steam shell in section and a plan view of the support.

Fig. 5 is a longitudinal section on line 5-5 of Fig. 6, showing the steam shell provided with a baffle member.

Fig. 6 is an enlarged cross section on line 6-6 of Fig. 5, showing the baffle member in normal position.

Fig. 7 is a cross section analogous to Fig. 6 showing the baffle member moved into position to close all the perforations in the steam shell except those exposed through the elongated slot in the baffle member.

Fig. 8 is an enlarged fragmental section on line 8-8 of Fig. 4, showing a detail of the means for extending the steam pipes through and securing them in an end plate of the steam shell.

Fig. 9 is a fragmental semi-diagrammatic side view of the heater coil pipes showing their inclination relative to the horizontal line a-a.

Fig. 10 is a fragmental cross section on line 10-10 of Fig. 5 showing a pointer attached to the handle of the baffle member, used to indicate the position of the elongated slot therein.

Fig. 11 is a side view of a fabric puffer adapted to renovate large material such as dresses, skirts, coats, sheets of cloth and the like.

Fig. 12 is a plan view of the apparatus shown in Fig. 11 with the perforated top half of the shell removed to show the arrangement of the steam pipes.

Fig. 13 is an enlarged cross section on line 13-13 of Fig. 11, showing the contour of the shell, the arrangement of the steam pipes and means for securing the halves of the shell together.

Fig. 14 is a vertical section through the steam shell illustrating how fur trimmed garments are arranged to protect the fur while the cloth is being renovated.

Fig. 15 is an enlarged fragmental cross section through the perforated portion of the shell showing a canvas covering over the wire screen.

The fabric puffer comprises a support 16 that can be secured by screws 17 to a floor or table not shown. The upper end of the support is provided with channels 18, 19 for steam pipes 20, 21 that are secured therein by U-bolts 22, see Figs. 1, 3, 4, 11 and 12.

The pipes 20, 21 are threaded through an end plate 23 that is bolted to an outwardly extending annular flange on the base of the steam shell 24, and these pipes are secured to the end plate 23 by the opposing nuts 25, 26 that are also arranged to jam packing rings 27 against the plate and around the pipes to prevent leakage. The shell 24 is conical having its base end flanged outwardly and the flange secured by bolts to the plate 23; and the shell is tapered considerably so that the sleeves of garments can easily be slipped on and off the shell.

20 The pipes 20, 21 thus secured to the plate 23 and support 16 hold the steam shell 24 in a position so that sleeves of garments and like material can be slipped over the free end of the shell and placed in position to be 25 renovated.

The pipes 20, 21 are extended a considerable distance into the shell and secured to a pipe head 28 to form a coil adapted to heat the interior of the shell and prevent a condensation of steam therein when the appliance is in use. In the coil shown in Figs. 11 to 14 additional pipes 20' and 21' are added thereto and joined by pipe connections 28'.

35 The inlet pipe 20 of the coil has its other end connected by elbow 29 and coupling 30 to one arm of a T-pipe 31 that has another arm connected by a pipe 32 to the top of a boiler not shown. The outlet pipe 21 has 40 its other end connected by a pipe 33 to the bottom of the boiler so that steam can pass downwardly through the coil to heat the shell as described.

The heating coil is arranged so that its 45 pipes incline downwardly throughout their length as diagrammatically illustrated in Fig. 9. As seen therein the pipe 20 throughout its length is arranged above the horizontal line $a-a$, but from its inlet end b inclines downwardly toward the line where it is connected to the head 28 which is also inclined downwardly as seen in Fig. 2. Pipe 21 is connected to the lower end of the head 28 and then inclined downwardly until 50 its outlet end c is considerably below the line $a-a$ so that water will flow by gravity out of the coil. This also is true of the coil shown in Figs. 12, 13.

The steam distributor pipe 34, and also 55 pipe 57 shown in Figs. 12, 13, are secured in this end plate 23, as are the pipes 20, 21, and they extend through the shell the length of the heating coil and have their ends closed by the caps 35.

60 The other end of pipe 34 is connected to

an arm of the T-pipe 31 by pipe connections 36 in which there is a valve 37, which when open permits dry steam from the boiler to discharge into the shell 24 through perforations 38 in the pipe.

70 The perforations 38 are preferably on the underside of the pipe 34 so that the steam will discharge downwardly and not upwardly toward the perforations 39 in the shell. This arrangement of the perforations 38 is 75 to prevent moisture from being discharged through the perforations 39 into the goods being renovated.

A disk 40 is secured in the shell 24 adjacent the cap 35, so that an end portion 41 80 of the shell will not be heated. This unheated portion is to enable operators to place the sleeves of garments and the like on the shell without burning their hands.

A fine mesh wire screen 42 is placed over 85 the perforations 39 and has its edges soldered to the shell; and the purpose of this screen is to evenly spread the steam so that it will penetrate all parts of the goods being renovated. It is understood that a cloth 43 is 90 placed over the wire screen 42 when in use as indicated in Figs. 14 and 15, and the purpose of the cloth is to protect the garments or material from injurious contact with the apparatus.

95 If desired the apparatus shown in Figs. 1 to 4 can be provided with means for closing nearly all of the perforations 39 so that the full charge of steam in the shell will be concentrated through a small number of 100 the perforations for the purpose of cleaning hems, seams and folded portions of garments.

A baffle member 44 is loosely fitted into the shell 24 and normally lies in the position 105 shown in Figs. 5 and 6; and it is connected to a handle 45 by a stem 46 that extends through a stuffing box 47 on the disk 40.

The handle 45 can be turned to rotate the baffle member 44 on its longitudinal axis 110 from its normal position shown in Fig. 6 to that shown in Fig. 7 to thereby cover all the perforations 39 except those exposed through the elongated slot 48 in the baffle member; so that a seam, hem or folded 115 portion of a garment can be arranged over the uncovered perforations 39 to receive the full charge of steam.

A pointer 49 is secured to the handle 45 and arranged to point in the direction of the 120 slot 48 to indicate its position when the baffle member is moved out of normal position.

As previously stated the fabric puffer hereinbefore described is especially adapted for use in renovating the sleeves of garments 125 and other material of sleeve-like form.

For use in renovating bodies of garments or large material the apparatus is enlarged and the contour slightly changed.

The shell 124 is supported in the same way 130

as shell 24, except that the pipe 34 and an additional pipe 57 are secured to the support 16 to aid in supporting the weight of the heavier shell 124, and a bracket 116 is bolted to the support 16 for bracing it.

The shell 124 comprises an upper half 50 and a lower half 51 that are arranged with a gasket 52 between them; and they are secured together by screws 53.

Preferably the shell 24 is elliptical in cross section. It is understood, however, that the surface of the part 50 can be flat or rounded as desired.

The part 50 is provided with perforations 39 over which the screen 42 is arranged and secured; and a canvas 43 is secured over the wire screen; but, for the sake of clearness in illustrating the apparatus, the canvas is omitted from the drawings, except in Figs. 14 and 15.

A wall 54 divides the interior of the shell 124 into chambers 55 and 56; and a steam distributor pipe 57 is provided for supplying the chamber 55 with dry steam independently of the other chamber. That is the pipe 57 is perforated a part of its length and discharges steam only into the chamber 55; while pipe 34 is perforated throughout its length and discharges steam into both chambers. Pipe 34 is controlled by a valve 37 and pipe 57 is controlled by a valve 58; so that when valve 37 is closed and valve 58 open only the chamber 55 will be available for renovating. The purpose of this arrangement is to provide a means for steaming garments that are trimmed with fur.

As illustrated in Fig. 14 a garment 59 having a fur trimming 60 is arranged on the apparatus so that the fur is not exposed to the steam discharging from the chamber 55; it being understood that valve 34 is closed and valve 58 open so that only chamber 55 is supplied with steam. By this arrangement of the chambers and supply of steam thereto, fur trimmed garments can be renovated without injury to the fur.

A pipe 61 controlled by a valve 62 is provided for draining water from the shells 24 and 124. Chamber 55 is provided with a by-pass 63 to the pipe 61 as shown in Figs. 13 and 14; and a port 64 adjacent the discharge end of the by-pass 63 connects the by-pass with the chamber 56 by which means water is drained from the chambers 55, 56.

In operation dry steam passes from the top of a boiler through the heating coil in the apparatus, and back to the bottom of the boiler so as to maintain a temperature in shell 24 or 124 that will prevent condensation of steam therein when in use.

When the sleeve of a garment is to be renovated it is placed over the shell 24 and valve 37 opened to charge the shell with dry steam; that then passes through the perforations 39 to be evenly spread by the

screen 42 and cloth 43 so that the portion of the sleeve over the perforated portion of the shell will be evenly penetrated by the steam. The action of the steam on the goods will not only clean it but will cause the nap to stand in normal position and appear to be new.

The same operation applies to the shell 124 except that it is provided with means for treating garments that are fur trimmed as previously described.

What we claim as our invention is:

1. A fabric puffer including a support; a conical steam shell having a flanged end secured to said support and having perforations through a portion thereof; means for supplying dry steam to the interior of said shell; a fine mesh wire screen having its edges soldered to the shell and arranged over the perforated portion thereof to evenly spread the steam discharging from the shell, and means within said steam shell for closing a portion of the perforations through said shell.

2. A fabric puffer including a support; a conical steam shell having a flanged end secured to said support and having perforations through a portion thereof; means for supplying dry steam to the interior of said shell; a fine mesh wire screen having its edges soldered to the shell and arranged over the perforated portion thereof to evenly spread the steam discharging from the shell, and a baffle member within said shell; and a handle adapted to be actuated to rotate said baffle member to close part of the perforations through said shell.

3. A fabric puffer including a support; a conical steam shell having a flanged end secured to said support and having perforations through a portion thereof; means for supplying dry steam to the interior of said shell; a fine mesh wire screen having its edges soldered to the shell and arranged over the perforated portion thereof to evenly spread the steam discharging from the shell, and a baffle member in said shell that has an elongated slot therethrough; and means for actuating said baffle member to close all the perforations in said shell except those exposed through the slot in said baffle member.

4. A fabric puffer including a support; a conical steam shell having a flanged end secured to said support and having perforations through a portion thereof; means for supplying dry steam to the interior of said shell; a fine mesh wire screen having its edges soldered to the shell and arranged over the perforated portion thereof to evenly spread the steam discharging from the shell, and a baffle member in said shell that has an elongated slot therethrough; a handle for actuating said baffle member to close all the perforations through said shell except those exposed through the slot in said baffle mem-

ber; and a pointer on said handle to indicate the position of the slot when said baffle member is moved from its normal position.

5. A fabric puffer including a support; a conical steam shell arranged horizontally and having perforations through an upper portion thereof; an annular flange extending outwardly from the base of said shell that is bolted to said support; means for supplying dry steam to the interior of said shell and discharging it in a direction opposite to the perforations through said shell; means for evenly spreading the steam as it is discharged from the shell; and a heating coil traversing said shell that inclines downwardly from the inlet to the discharge end thereof to prevent an accumulation of condensed steam therein for the purpose specified.
- 20 6. A fabric puffer including a support having channels therein; steam pipes secured by U-bolts in the channels of said support; a shell having an end plate through

which said pipes are extended and secured, one of said pipes traversing said shell to heat it and the other pipe perforated to supply dry steam thereto; and a portion of said shell perforated over which garments can be renovated.

- 25 7. A fabric puffer including a support, a shell; steam pipes secured to said support and extended into the shell to form a heating coil; a wall for separating the interior of said shell into steam chambers; a steam distributor pipe for supplying steam to both chambers; another steam pipe for supplying steam to only one of the chambers; valves for opening and closing said distributor pipes; and a screen covered perforations above the steam chambers over which clothing can be renovated.

In witness whereof, we have hereunto affixed our signatures.

HAROLD L. WATKINS.
LA. VERE J. EVELAND.
